AUGUST E. ANDERSON, OF MONTCLAIR, NEW JERSEY

SPARK PLUG

Application filed November 8, 1932. Serial No. 641,765.

My invention relates to spark plugs for internal combustion engines, and more particularly designed as an improvement upon the devices described and claimed in my co-pending application filed April 11, 1932, Serial No. 604,592.

One object of my invention is to place an insulated wall directly between the electrodes in the spark gap in order to concentrate the high voltage current to one spot or to one surface of the electrodes. It is a well known fact that the high voltage current generally used in the combustion engines of today will find other paths than through the gap of the electrodes, thereby weakening and sometimes fouling the spark plug. With the insulated wall, however, as shown in the accompanying drawing, these drawbacks are not only eliminated but a hotter spark is obtained and with more efficiency at all times.

My other object providing an insulated wall between the electrodes, is to form a flat spark rather than a round spark as would be the case if the insulated wall were not there. It has proved to be of great advantage to fire the compressed fuel charge with a flat spark because the gases are more completely burned and therefore give a quicker action and more power to the engine.

Still another object of providing an insulated wall between the gap of the electrodes, is that by this wall the grounded electrode is completely insulated from the high voltage current or central electrode except across the edge of an insulated wall to the grounded electrode, and thereby eliminating the chances of fouling the spark plug by carbon or oil. If it happened that carbon or oil should deposit on the said wall, the action of the electrical current and the heat would burn away all such deposits, and would not foul the spark plug but rather act as a stepping stone to the grounded electrode.

Still another object with the said insulating wall is to be able to obtain the advantage of a longer spark gap. As the electrodes burn away, I have found that with the support of this wall, the spark would jump a

greater distance than if the said insulated wall were removed. Furthermore, with this advantage the spark gap would not have to be adjusted to a set gap, as is now the case with the average spark plug.

In the accompanying drawing, one embodiment of my invention is illustrated, and Fig. 1 shows a longitudinal, axial section of the improved spark plug;

Fig. 2 a transverse section along line 2—2 of Fig. 1 and

Fig. 3 a fragmentary sectional view of the lower portion of the spark with a slight modification of my improved device.

In the drawing reference numeral 10 represents the metal housing of the plug with a securing nut 11 threaded thereon as at 31 to hold the dielectric or porcelain insulator 12 in position therein. The insulator is in the usual manner provided with an enlarged body 70 portion 9 tapering into the upper neck portion 21 by way of a shoulder 20 and likewise tapering downwardly into the shank 24 by way of a shoulder 23. Corresponding seats with packings for said shoulders are 75 provided in the nut 11 and housing 10 all in known manner.

The neck portion 21 of the insulator extends through a corresponding opening of the nut 11 which latter is preferably rounded 80 or dome-shaped to prevent tampering with the plug after its assembly. Into the top of the neck portion the electrode 15 is threaded, extending with its long narrow portion right through the enlarged bore of the insulator 12 to its lower end. Above the head 16 of this electrode 15 the same is adapted to receive a screw cap 17 for securing the lead-in wire.

An annular space 14 is provided in the exteriorly threaded end 19 of the housing 10 around the insulator shank 24. The latter has in its lower end a fairly deep chamber 13, opening downwardly and within this chamber is furnished, as an extension to the porcelain insulator, a tapering annular wall or curtain 26, the lower edge of which terminate about level with the lowermost end of the electrode 15, but well within the lower edge of the chamber.

In the end portion 19 of the housing is secured the ground electrode 18, preferably in the form of a straight, short pin which extends across the annular space 14 and through 5 an enlarged opening 27 in the shank 24 and terminating in the chamber 13 near the edge of the curtain or tapering wall 26 and about level therewith.

As in my above-named copending application, the spark gap 25 is also here located 10 within the chamber 13 formed in the end of the porcelain insulator 12. The additional advantage is however here provided that the spark will have to jump between the two 15 electrodes 15 and 18 over the edge of the tapering wall or curtain 26 thereby causing the spark to be flat instead of round and also creating a longer spark gap.

In Fig. 3 is shown a modified form of the 20 ground electrode 28, which therein is shown as a hook-shaped, bent wire instead of the straight pin 18 in Fig. 1. This hooked, ground electrode 28 is secured with its straight arm 29 in the lower end 13 of the 25 housing, but instead of running through an opening in the porcelain shank 24 as in Fig. 1, it is now bent around the lower edge of the shank with an arm running upward in about 30 45° inclination into the chamber 13 up to a point about level with the edge of the curtain 26 and the end of the electrode 15. From there it runs straight up a short distance above said edge and forming a tip 30.

By this means assembling of the parts is 35 facilitated while retaining the advantages of the flat spark and the long gap.

It should be understood that the invention is not limited to the details of construction here shown and disclosed but that those may 40 be varied widely without departing from the spirit of the invention as defined by the claims.

I claim:

1. In a spark plug having the usual electrodes, a metal housing member and an insulator core member firmly seated therein, said core member being provided with a downwardly open chamber, an annular space being formed between the lower ends of said 50 members; the main electrode being mounted axially in said core members and the ground electrode secured in said housing member and extending across said space into said chamber, the spark points being situated within said chamber well beyond the lower edge of the core member; the combination with 55 means forming an obstruction in the spark gap, thereby creating a substantially flat spark between the spark points.

2. In a spark plug having the usual electrodes, a metal housing member and an insulator core member firmly seated therein, said core member being provided with a downwardly open chamber, an annular space being 60 formed between the lower ends of said

members; the combination with an annular wall forming a continuation of the core member within said chamber and terminating well within the chamber, the main electrode being mounted axially in the core member with its spark point substantially level with the edge of said annular wall, the ground electrode being secured in said housing member and having its spark point situated in said chamber outside of said annular wall, the edge of said wall thus forming an obstruction 70 between the spark points in the spark gap. 75

3. In a spark plug having the usual electrodes, a metal housing member and an insulator core member firmly seated therein, said core member being provided with a downwardly open chamber, an annular space being formed between the lower ends of said members; the combination with an annular wall forming a continuation of the core member 80 within said chamber and terminating well within the chamber, the main electrode being mounted axially in the core member with its spark point substantially level with the edge of said annular wall, the ground electrode being secured in said housing member, and having an upwardly inclined arm 85 terminating with a spark point extending into said chamber above the edge of the annular wall, said edge thus forming an obstruction 90 between the spark points in the spark gap. 95

4. In a spark plug having the usual electrodes, a metal housing member and an insulator core member firmly seated therein, said core member being provided with a downwardly open chamber, an annular space being formed between the lower ends of said members; the main electrode being mounted axially in said core members and the ground electrode secured in said housing member and extending across said space into said chamber, the spark points being situated within said chamber well beyond the lower edge of the core member; the combination with 100 means forming an obstruction in the spark gap, thereby creating a spark gap of more than ordinary length.

5. In a spark plug having the usual electrodes, a metal housing member and an insulator core member seated therein, said core member being provided with an open ended chamber, an annular space being formed between the said members; the main electrode being mounted in said core member and the ground electrode secured in said housing member and extending across said space into said chamber, the spark points being situated within said chamber; the combination with 115 means forming an obstruction in the spark gap, thereby creating a substantially flat spark between the spark points.

In testimony whereof I affix my signature.

AUGUST E. ANDERSON.
